UNITED STATES PATENT OFFICE.

ALBERT L. MATTESON, OF BATTLE CREEK, MICHIGAN.

AUXILIARY SIGHT-FEED.

1,295,184.

Specification of Letters Patent.

Patented Feb. 25, 1919.

Application filed November 9, 1917. Serial No. 201,122.

To all whom it may concern:

Be it known that I, ALBERT L. MATTESON, a citizen of the United States, residing at Battle Creek, in the county of Calhoun and 5 State of Michigan, have invented a certain new and useful Auxiliary Sight-Feed, of which the following is a specification, the principle of the invention therein being shown and the best mode I have contemplated for carrying that principle into practice.

The invention is a sight feed to be used in connection with a reservoir, mechanical force feed or other lubricator employed in 15 supplying lubricants to steam apparatus and engines in general.

A characteristic feature and important object of my invention is a steam column formed with a transverse conduit through 20 which lubricant is fed from a lubricator or storage under valve control through a sight feed glass from which it is diffused in said steam column and passes into an engine.

Aside from providing a simple, compact, 25 economic and effectual auxiliary sight feed, another object of my invention is to provide means whereby the glass to the sight feed column may be replaced in case of breakage without retarding the operation of the lubricator supplying oil therethrough.

A further object of my invention is to provide means whereby should breakage from any cause arise in the lubricator feeding oils thereto the water in the sight feed 35 column cannot flow into said lubricator or its pump.

A still further object of my invention is to produce a device of the character which while having the features referred to above 40 will have advantages in mechanical construction hereinafter set forth in the following specification, shown in the drawings and defined in the appended claim.

In the drawings forming a part of this 45 specification;

Figure 1, is a side elevation of a preferred embodiment of my auxiliary sight feed.

Fig. 2, is a vertical section of the same.

Fig. 3, is a cross-section on the line $x-x$ of 50 Fig. 1.

Fig. 4, is a reduced transverse view of the steam column on the line $z-z$ of Fig. 2.

Like marks of reference refer to corresponding parts in the different views, in 55 which A, is an integrally formed steam column the lower extremity of which is in-

ternally screw-threaded and adapted to be connected with an elbow or other tubular connection to the feed pipe of a steam cylinder of a pump or engine. This column near 60 its lower extremity is expanded in globular form as 1 through which a passage 2 is formed that leads from a reservoir or lubricator, not shown, the latter of which connects on the left with an L-valve fixture 3 65 screw-threaded into an offset 4 of said globular form.

The expanding of the column is for the purpose of affording a steam conduit about the lubricant passage 2 whereby fluidity of 70 the latter will be insured under all atmospheric conditions. The column A at its top has an offset 5 and an aligned offset 6 near its lower end, the former of which receives the screw-threaded boss of the sight feed indicator top, 7, the latter the screw-threaded 75 boss of the sight feed indicator bottom A.

The sight feed indicator is a glass open-ended tube B fitted at one end into the top 7 and at its opposite end with the bottom 8 80 and made steam, oil and airtight by means of the ring packings 10 and gasket nuts 11 in the customary manner.

The top 7 is formed with an offset opening 12, one end of which communicates with 85 the column A, the other end opening above the space in the sight feed glass B, and the column A in case of emergency, the same in no wise, materially differing from similar apparatus employed with water gages on 90 steam boilers.

The bottom 8 is formed with an offset 14 screw-threaded into the offset 6 of the column A and is bored out to form a passage 15 leading through the offset 6 to a vertical 95 drainage 16 controllable by a needle valve 17 aligned with said boss on the opposite side of said bottom.

Centrally within the base upon which the sight feed glass B rests, an opening is 100 formed having a funnel-shaped bottom upon which a small ball valve 18 fits. The bottom of this valve seat has a small opening communicating with the central passage 15 and is directly controlled by a needle valve 105 19 entering the bottom 8 from below and in central alignment with the sight feed D.

Screw-threaded into the opening above the valve 18 a small lubricant nozzle 20 is fitted. This nozzle extends upwardly with 110 in the sight feed glass B sufficiently far to permit a person to observe the passage of

oil emitted therefrom in the operation of the indicator.

Piercing the enlarged or globe-shaped portion 1, of the column A from one side is a hole and also communicating with the passage 2 in alinement therewith is a valve seat opening 20', see Fig. 4, the latter of which is under control of a needle valve 21 fitted within a boss 22 of said column. This valve 10 is for the purpose of supplying lubricant to an engine in case the indicating glass B leaks about its fittings or becomes broken, or during time required to install a new glass, in any of which instances the valves 13 and 15 19 are closed to preclude either the passage of steam from the column A or lubricant from the passage 15 to pass their respective valve openings.

Characteristic features of the indicating 20 gage have hereinbefore been enumerated and described, I will now describe the general operation of the device as operating on an engine both being under normal working conditions.

25 The column A having been attached to the lead pipe or steam cylinder of an engine, an L valve fixture 3 connected with an oil supply or lubricator, or in case said L fixture is omitted, the offset 4 of said column 30 is connected with said oil supply or lubricator, steam will enter the column A and through the valve controlled passage 12 enter the sight feed glass B in which place the steam will condense and form a column of 35 water. Water having sufficiently formed in the indicating glass B to a level above the nozzle 20 therein, lubricant is then fed from an oil supply, a lubricator for instance, and enters through the openings 2 and 15, from 40 the latter opening of which it passes under control of the needle valve 19 and globe valve 18, into the nozzle 20 from which it

rises drop by drop through the water column and floating on the latter's surface passes out through the opening 12 and in infinitesimally small particles is diffused with the steam in the column A, and through gravity force enters the engine. 45

To those skilled in the art to which the invention applies a more extended explanation of the operation and advantages of my auxiliary sight feed is believed will not be necessary. 50

Having described my invention, what I claim and desire to secure by Letters Patent 55 is:—

An auxiliary sight feed, the combination with a lubricator, a water column sight feed glass having an oil feeding nozzle extending upwardly within said sight feed glass 60 and communicating with lubricant passage from said lubricator, and a valve controlling the passage at the top of said sight feed glass water column, of a steam column extending about said lubricant passage and 65 communicating at its top with said valve controlled passage to said sight feed glass water column, a valve seat having an opening entering from said steam column about said lubricant passage into said lubricant 70 passage, a valve controlling said valve seat opening, a needle valve interposed within said lubricant passage between said steam column and the nozzle in said sight feed glass for regulating the flow of lubricant 75 through said passage, a ball valve interposed between said nozzle and the seat of said needle valve, to prevent back flow from said sight feed glass, and means to drain said lubricant passage, substantially as specified. 80

ALBERT L. MATTESON.
